[57] ABSTRACT

A device which scans the density of successive increments of a cigarette rod produced in a cigarette making machine, is used to control the mean weight of the tobacco in that rod with a view toward maintaining substantially constant the number of cigarettes produced having a weight falling below a preselected level. Signals produced by the scanner are used to control the quantity of excess tobacco removed from the filler stream formed therein by a trimming device, thereby controlling the quantity of tobacco placed in said rod.

**MANUFACTURE OF CIGARETTES AND OTHER
TOBACCO-FILLED ROD-LIKE ARTICLES**

In cigarette making machines there is commonly provided a scanning device, for example a Beta ray device, for detecting the density of the cigarette rod as it passes the scanning device and for controlling the amount of tobacco forming the cigarette, with a view to maintaining the tobacco content in the cigarettes constant as far as possible. For example, the tobacco content in terms of weight per unit length may be varied by varying the distance of a trimmer from a suction band carrying the tobacco filler, for example as described in U.S. Pat. No. 3,089,497. The tobacco filler is commonly enclosed in a continuous web, usually of paper, which forms the cigarette wrapping.

With some cigarette making machines, for example the Molins Mark 8 machine, it is possible to obtain a low figure of standard deviation σ (for example 2.5 percent) where

$$\sigma = \sqrt{\frac{\sum (W - \bar{W})^2}{N}} \times 100,$$

W being the nominal weight of the cigarettes and W being the actual weights of each of N cigarettes. Accordingly it has been possible to set the nominal weight (i.e. the mean weight as controlled by the Beta ray or other measuring device) at a relatively low value which, owing to the low standard deviation, nevertheless resulted in substantially all the cigarettes having a weight above a threshold value T which was a value below which a cigarette manufacturer would want no more than a certain very small percentage of cigarettes (for example about 0.135 percent) to be. The actual percentage below T which could be tolerated depended upon any given manufacturer's requirements in relation to the desired quality of his cigarettes, as did the chosen value of T . The threshold weight T may for example be 7½ percent below the mean weight.

One aspect of the present invention is concerned with a departure from that previous concept of cigarette manufacture. This departure is based on a concept of varying the mean weight of the cigarettes continuously in order to maintain substantially constant an operating characteristic relating to the number of cigarettes having a weight below a predetermined threshold weight T which may or may not be the same as the threshold weight T specified previously. In one preferred system according to this invention, all cigarettes having a weight below the value T are automatically ejected from the production line. These cigarettes may subsequently simply be stripped so that the tobacco filling can be re-used. Alternatively these underweight cigarettes may in principle be subjected to a further test, for example a continuous filling-pressure test, (e.g. as described in U.S. Pat. No. 3,633,590), after which they are ejected and stripped only if they have also failed the further test.

This invention enables a cigarette making machine to operate at a lower mean filling weight than hitherto, with a consequent saving of tobacco.

This will be further explained with reference to the accompanying drawings. In these drawings:

FIGS. 1 and 2 are graphs showing weight distributions of cigarettes during manufacture;

FIG. 3 is a diagrammatic drawing of parts of one apparatus according to this invention; and

FIG. 4 is a block diagram of a system wherein several cigarette making machines are controlled by a central computer.

FIGS. 1 and 2 are graphs showing cigarette weight (X) against proportional distribution (Y). That is to say Y represents the proportion of cigarettes which have any given weight X.

The curve C_1 in FIG. 1 is a curve corresponding to a cigarette making system designed to produce only a very small and insignificant number of cigarettes below a threshold weight of T , the mean weight in this case being M_1 . In a system operating according to the present invention the mean weight may at any given moment be for example M_2 , giving a curve of cigarette distribution C_2 . With this curve C_2 there is an area A_1 (shown shaded) representing the number of cigarettes which have a weight less than T . These underweight cigarettes may according to this invention be ejected and stripped so that the tobacco contained in those cigarettes can be re-used. The important point to note, however, is that M_2 is less than M_1 , so that cigarette manufacture according to the curve C_2 will use less tobacco while still ensuring that substantially no cigarettes are produced with a weight less than T .

In controlling a cigarette making operation according to this invention, the mean weight is preferably varied automatically in order to keep substantially constant the number of cigarettes having a weight which falls below the value T . This control is desirable because the standard deviation of the cigarette making machine may increase or decrease slightly from time to time, giving a flatter or sharper curve C_2 . Variation in standard deviation may for example be caused by variations in the quality of the tobacco or in the tobacco moisture content or temperature. If the mean weight were kept constant at M_2 , a temporarily flatter curve (i.e. resulting from a higher standard deviation) would result in more cigarettes falling below T in weight. This is illustrated by FIG. 2, which again shows the curve C_2 (as in FIG. 1) and shows also a flatter curve C_3 which represents the weight distribution given by a higher standard deviation but with the same mean weight M_2 . It will be seen that the shaded area A_2 , representing the number of cigarettes having a weight of less than T , is larger than the area A_1 in FIG. 1. In a preferred system according to the present invention, when the standard deviation increases in this way, the mean weight is automatically increased to a value M_3 ; this gives a weight distribution curve C_4 below which the area to the left of the threshold weight line T is approximately the same as the area A_1 . On the other hand, during times when the standard deviation is lower than that represented by the curve C_2 (i.e. giving a sharper weight distribution curve) there is a smaller number of cigarettes falling below the weight T , and the mean weight is preferably, according to this invention, reduced automatically so as to restore the number of cigarettes below T to the same value as before, as represented by the area A_1 .

Various ways of computing the standard deviation D may be used. For example, the signal from the scanning device may be chopped into pulses representing the density of successive increments of the cigarette rod, and the pulses for each cigarette may be integrated (for example as described in U.S. Pat. No. 3,662,272) to obtain an indication of the mean weight of each cigarette in turn. As seen in FIG. 4, in the case of a cigarette

factory including a number of cigarette making machines, each machine may have a recorder unit for recording information (e.g. relating to cigarette weights) which is transmitted at regular intervals to a central computer serving all the machines, for example as described in U.S. application Ser. No. 840,279, filed July 9, 1969. This computer receives information from each machine in turn, for example about once a minute, and calculates the standard deviation; this computer may also take account of other factors (for example the moisture content and temperature of the tobacco) in sending back a signal to each machine to change the mean weight if necessary.

The standard deviation may be derived by counting up the number of cigarettes obtained from a given length of the cigarette rod which have a weight coming between two predetermined limits. For example the lower limit may be the threshold weight (or zero) and the upper limit may be a value greater than the mean weight and can be chosen so that the proportion of cigarettes coming between these two limits bears an approximately linear relationship to the standard deviation.

As an alternative to the arrangement described, in which the standard deviation of each machine is computed from information transmitted at intervals to a central computer, each machine may have provision for computing continuously the standard deviation on the basis, for example, of a predetermined number of the last cigarettes to have been made up to any particular instant.

In general, as an indication of a possible mode of operation according to this invention, the threshold ratio S may be approximately equal to 3, where $S = (M_2 - T)/\sigma$.

One problem which arises in carrying out this invention on the basis of cigarette weight detection is that, where the standard deviation is say 2.5 percent, the instrument error in detecting the cigarette weight may be as high as 1.1 percent. There is consequently what may be termed a low signal to noise ratio, for example 2.5:1.1. The ratio would be better (i.e. higher) if the instrument error were smaller, but it is not easy to reduce the instrument error or "noise," especially in the case of a Beta ray or other scanning device which is arranged to have a fast response so as to be sensitive to variations between very short increments of the cigarette rod, for example of the order of 1 or 2 mm. in length.

A preferred system according to this invention, in which an improved signal to noise ratio can be obtained, is one in which the mean weight of the cigarettes is controlled by sensing the density of short cigarette sections of predetermined length, for example 10 to 12 mm. The short sections are preferably the end portions of the cigarettes. For example, in the case of filter-tipped cigarettes, the end portions may be at the unfiltered ends of the cigarettes (i.e. remote from the filter). Alternatively, the arrangement may be one in which the cuts separating adjacent cigarettes pass through the centers of the end portions. The end portions may be filled with tobacco at a greater density than the remainder of the cigarettes. The standard deviation of the tobacco filling in the end portions may be of the order of say 5 percent. The "noise" or instrument error in reading ends density is higher than for cigarettes as a whole, for example, 1.65 percent, but

the signal to noise ratio (e.g. 5:1.65) is nevertheless better than in the case of a control based on the cigarette as a whole. Consequently, according to this method, fewer satisfactory cigarettes (on the basis of ends quality) will be rejected and fewer unsatisfactory cigarettes will be allowed to proceed. Moreover it is significant that this method of control directly governs the ends quality which is important to the consumer.

According to another aspect of this invention the density signal for each cigarette or cigarette end (or for each increment) is not taken as an absolute reading but is assessed with reference to a running mean reading taken from a number of adjacent cigarettes. For example a time delay device may be used so that each signal is taken with reference to a mean value based on the signals derived from two or more upstream cigarettes (or increments) and two or more downstream cigarettes (or increments); alternatively the reference point may be the mean of the last three or more cigarettes or increments. The mean reading from the adjacent cigarettes may be used as a reference from which to determine the cigarette mean relative density. The actual reference point may however in fact be based on an absolute value with a running correction (i.e. a bias in one direction or the other) derived from the mean readings of the adjacent cigarettes. By this means a degree of compensation can be obtained for short-term variations in tobacco filling power. For example, if the filling power were to drop temporarily owing to an increase in the proportion of shorts, with a consequent increase in the mean weight, a cigarette which is somewhat lighter than the mean of the few adjacent cigarettes containing the same sort of tobacco might still be above an absolute threshold weight, but would be correctly rejected on the basis of a comparison with the mean since it would be inadequately filled having regard to the low filling power of its tobacco; in other words it would be liable to be too soft. The converse occurs where the filling power of the tobacco is temporarily higher than average; that is to say, comparison with the mean of the adjacent cigarettes may save a slightly light cigarette from being ejected where it is in fact sufficiently firm to be accepted.

FIG. 3 shows an example of a system according to this invention for varying the mean weight of the tobacco in the cigarette rod in response to the mean density of the end portions.

As shown in FIG. 3, a continuous cigarette rod 2 (i.e. before it is cut into cigarette lengths) passes through a guide tube 4 which has openings through which Beta rays from a source 6 pass. After passing through the rod, the beam of Beta rays enters a radiation detector which, in the example shown, is an ionization chamber 8 comprising a shell 10 and an electrode 12 which is electrically insulated from the shell. In addition there is a balance unit comprising a radiation source 6A and an ionization chamber 8A which is similar to the ionization chamber 8. The amount of radiation reaching the chamber 8A is controlled by means of a movable absorption member 14 which in the arrangement shown is pivotally mounted at 16.

A D.C. potential is connected across terminals 18 and 20 on the shells of the ionization chambers. Consequently at a point 22 on a conductor connecting the electrodes 12 and 12A there is a signal of which the strength depends upon the density of the cigarette rod. The signal at 22 is fed via an amplifier 24 and a control

input 26 to a point 28 connected to two discriminator circuits 30 and 32. These discriminator circuits are sensitive respectively to positive and negative signals. Each is connected to a relay 34 or 36 which controls the connection of a voltage supply to a reversible electric motor 38. When the signal at 28 becomes positive or negative by more than a predetermined amount, signifying that the rod density is too low or too high, one or other relay is operated by the appropriate discriminator circuit so as to drive the motor 38 in one direction or the other so as to correct the rod density. The motor 38 may for example control the position of a tobacco trimmer 50 as already mentioned.

From the output of the amplifier 24 there is a connection to a switch 40 which opens and closes rapidly under the control of a rotating cam 42. The cam rotates at a speed corresponding to one revolution per cigarette length and is arranged to close the switch while each cigarette end portion is passing through the scanning device (i.e. past the radiation source 6). The signal from the end portions is thus transmitted to a computer 44. This computer, as already mentioned, may calculate the standard deviation in various ways; it thus provides an output signal to the control input 26 so as to vary the mean weight. In other words, under the control of the computer, the control input introduces a positive or negative signal (as the case may be) so as to change the mean weight of the tobacco in the rod, for example by moving the trimmer 50; i.e., the mean position of the trimmer is changed.

Instead of the control from the computer being introduced by means of the control input 26, it may for example be exercised by moving the absorption member 14 of the balance unit. The member 14 may for example be movable into different positions by means of an electric servo motor in the well-known manner conventionally provided in control systems. In this case the member 14 may for example be in the form of a disc mounted to rotate about an axis parallel to the beam from the radiation source 6A, the edge of the disc being so shaped (i.e. like a cam) as to intersect the beam by a variable amount depending upon the angular position of the disc.

Downstream of the scanning device the rod is cut into cigarette lengths by means of a cut-off device (not shown). Still further downstream there is an ejector device 52 of standard configuration for ejecting cigarettes of which the ends have a density falling below the threshold level. The ejector device may also eject over-heavy cigarettes.

What we claim as our invention and desire to secure by Letters Patent is:

1. A method of making cigarettes or the like comprising enclosing a tobacco filler in a continuous web to form a continuous rod adapted to be cut into cigarette lengths, detecting the density of those portions of the rod intended to become cigarette end portions by means of a scanning device which is arranged in a position along the path of the rod and gives output signals

5 relating to the density of the tobacco filling in the rod, the output corresponding to the density of the intended cigarette end portions, varying the amount of tobacco placed in the cigarette rod in response to said output signals to maintain substantially constant the number of cigarette end portions having a mean density which falls below a predetermined level.

2. A method according to claim 1, including chopping the output signals from the scanning device into a sequence of pulses representing the densities of successive short increments of the rod.

3. A method according to claim 1, including ejecting cigarettes having end portions of which the average density is below a predetermined level.

4. A method according to claim 1, including comparing the density signal for each intended cigarette end portion to the mean density of a few adjacent intended cigarette end portions.

5. Apparatus for making cigarettes or the like comprising means for wrapping a continuous web around a tobacco filler to form a continuous cigarette rod adapted to be cut into cigarette lengths; means for varying the mean weight of the tobacco filler; a scanning device which scans the cigarette rod and is arranged to provide output signals at intervals timed so as to correspond to portions of the rod intended to become end portions of the cigarettes; means for repeatedly computing the mean density of the intended end portions; and means for automatically varying the 10 mean density of the tobacco filler in response to the computed mean density of successive end portions so as to maintain constant the number of cigarette end portions obtained from a given length of rod having a mean density which falls below a predetermined level.

6. A method of making cigarettes or the like comprising enclosing a tobacco filler in a continuous web to form a continuous rod adapted to be cut into cigarette lengths, detecting the density of the tobacco in said rod with a scanning device arranged along the path of the rod to provide output signals related to the density of successive linear increments of the tobacco in said rod, comparing the signal from the scanning device for each linear rod increment to the mean of signals from a number of adjacent increments, and controlling the mean weight of the tobacco entering said rod in response to the results of said signal comparing.

7. Apparatus for making cigarettes or the like, comprising means for enclosing a tobacco filler in a continuous web to form a continuous cigarette rod adapted to be cut into cigarette lengths, a scanning device arranged along the path of the rod to provide output signals related to the density of successive linear increments of the tobacco in said rod, means for comparing the signal from the scanning device for each linear rod increment to the mean of signals from a number of adjacent increments, and means for varying the mean weight of the tobacco entering said rod in response to the output of said comparing means.
